(57) **CLAIM**

The ornamental design for an ultrasonic probe, as shown and described.

DESCRIPTION

FIG. 1 is a front view of an ultrasonic probe of a new design;

FIG. 2 is a left side view thereof;

FIG. 3 is a right side view thereof;

FIG. 4 is a plan view thereof; and,

FIG. 5 is a bottom plan view thereof.

The broken line in the interior of the circular element in FIG. 4 and the oval elements in FIGS. 1-4 are included for the purpose of illustrating environment and forms no part of the claimed design.
